(57) **CLAIM**

The ornamental design for an architectural separation baffle as shown and described.

DESCRIPTION

FIG. 1 is a perspective view of an architectural separation baffle showing our new design;

FIG. 2 is a top view thereof;

FIG. 3 is a bottom view thereof;

FIG. 4 is a front elevation view thereof;

FIG. 5 is a rear elevation view thereof;

FIG. 6 is a right side elevation view thereof; and,

FIG. 7 is a left side elevation view thereof.

The broken lines in the drawings depict portions of the architectural separation baffle that form no part of the claimed design. The architectural separation baffle is shown with a symbolic break in its length. The appearance of any portion of the architectural separation baffle between the break lines forms no part of the claimed design.
